UNITED STATES PATENT OFFICE.

EDWARD SCHULTZ, OF MAYWOOD, ILLINOIS, ASSIGNEE, BY MESNE ASSIGNMENTS, TO
MRS. E. A. LAUGHERY, OF CHICAGO, ILLINOIS.

COIN-OPERATED VENDING-MACHINE.

1,400,773.

Specification of Letters Patent. Patented Dec. 20, 1921.

Application filed December 26, 1919. Serial No. 347,351.

To all whom it may concern:

Be it known that I, EDWARD SCHULTZ, a citizen of the United States, residing at Maywood, in the county of Cook and State 5 of Illinois, have invented certain new and useful Improvements in Coin-Operated Vending-Machines, of which the following is a specification.

This invention relates to a coin-operated 10 vending machine adapted to dispense newspapers, periodicals, or other selected commodities.

The general construction of the parts 15 which form the delivery mechanism may, if desired, be much the same as that disclosed in Letters Patent No. 1,088,949, granted March 3, 1914, to Frank Warren, and accordingly the description to follow will be brief in its relation to such parts. 20 The coin mechanism herein disclosed embodies, however, a number of improved features which coöperate with the delivery mechanism in a novel and efficient manner, all as will be hereinafter pointed out at 25 length.

For its objects, this invention aims to provide a mechanism adapted to dispense a single paper or other article, only after the insertion of one or more coins totaling not 30 less than a predetermined number and value, and a mechanism that may be readily adjustable to operate with coins of different denominations, or with coins whose total number or value varies in accordance with 35 a desired plan. In addition, the parts of the present machine are so constructed and assembled as to be practically fool-proof, are securely protected from tampering, and are safe-guarded against effects of the 40 weather if the device be placed out in the open; and, furthermore, they are formed and arranged in a simple and durable manner, thus conducing to certainty in operation and low cost in manufacture. Numerous other 45 objects as well are also attained in this invention, many of which will hereinafter appear from the specification and claims.

The drawings.

50 A machine in which the present improvements may be incorporated is illustrated in the accompanying drawings in the manner following:

Figure 1 is a front elevation showing,

through a broken-away portion of the front 55 wall, the principal operating parts of the coin mechanism interiorly of the container; Fig. 2 is a fragmentary cross section there- through taken on line 2—2 of Fig. 1;

Fig. 3 is an enlarged elevation of one end 60 of the carriage;

Fig. 4 is a horizontal section of certain portions of the mechanism taken on line 4—4 of Fig. 1;

Figs. 5 to 10 inclusive are diagrammatic 65 views of the carriage latch mechanism, indicating the movements of these parts under various operating conditions;

Figs. 11 and 12 are fragmentary views of the two latch members, showing the charac- 70 ter of the opening in each;

Fig. 13 is a vertical section through the carriage, showing in elevation certain of the parts associated therewith;

Fig. 14 is a vertical section through the 75 carriage, showing its relation to the opening means for the coin chute gates; and

Fig. 15 is a view, in elevation, of the coin setting mechanism, the carriage and certain of the other parts being removed to better 80 exhibit the construction.

General assembly.

Preliminary to an exposition of the mechanism that is novel to this invention, it may 85 be mentioned that its use is contemplated in connection with a suitable container within which are housed the articles to be dispensed, as well as the mechanism by which the dispensing operations are accomplished. 90 This mechanism is mounted upon a partition plate which is removably positioned within the container, the articles to be dispensed lying upon one side of the plate, and the mechanism on the reverse side thereof. 95 Formed in the plate are suitable vertical slots through which pins are adapted to be projected so as to engage with the proximate article on the opposite side of the plate, these pins being carried upon a rock shaft which 100 is mounted within a vertically movable carriage whose function it is to elevate the articles after the pins have been engaged therewith. Through a suitable slot formed in the upper end of the container the 105 dispensing articles are projected therefrom a sufficient distance to be grasped by the hand. The elevation of the carriage is ac-

complished by some such means as a chain connected therewith, and having one end extended exteriorly of the container so that it may be operated by the purchaser. A 5 structure answering generally to the above is disclosed in the Warren patent above noted, but inasmuch as this invention is concerned primarily with a coin mechanism by which the dispensing operations are governed, a further detailed description of the latter is thought unnecessary.

The carriage.

The present mechanism is shown as 15 housed within a suitable container provided with a front wall 15, end walls 16, and a top or cover 17 which may be hinged in position and suitably held in place by means of any desired lock. On the inner sides of 20 the end walls are secured guides 18 for removably supporting therein a partition plate 19, on which the operating mechanism is mounted. At its lower end this plate is turned to provide a bottom 20 on which is 25 mounted the lower ends of a pair of guide rods 21, their upper ends being suitably supported as by means of a bracket 22 which is also secured to the partition plate. Mounted to slide upon these guide rods is the 30 carriage 23 that may conveniently be formed with spaced longitudinal rails 24 connected by vertical webs 25, suitable ears 26 being extended inwardly toward the guide rods 21 to slide thereupon. Bumpers or cushion blocks 27 may be arranged beneath the 35 carriage, as shown.

The carriage is further formed to provide 40 bearings within which is mounted a rock shaft 28 which carries a plurality of pins 29 each adapted for projection through slots 30 that are formed vertically within the partition plate. If desired, a dog 31 may be 45 positioned upon the rock shaft in operative relation to a cam plate 32 that is attached to the partition plate, so that the rock shaft 28 will be positively turned with each upward movement of the carriage for the purpose of projecting the pins 29 through the 50 slots 30 into engaging relation with the papers or other commodities that are arranged on the opposite sides of the partition plate. For raising the carriage a chain 33 may be 55 employed, having one end extended exteriorly of the container and passing over a pulley 34 that is mounted on the front wall of the container, so as to attach to the carriage inside. When constructed in this manner, papers or other selected commodities will be dispensed from the container 60 through a slot 35 that opens out upon the front wall 15 near its upper end.

The coin chute.

The mechanism that is peculiar to this 65 invention includes a coin chute whose re-

ceiving end 36, adjacent the delivery slot 35, may receive coins of a proper value. Means are provided for barring the entrance of coins when the supply of papers or other commodities is exhausted, consisting of a 70 finger 37 which is formed as part of a wire 38, pivoted as at 39, and having suitable spring means (not shown) for normally projecting one end 40 through an opening 41 that is formed in the partition plate. As 75 long as articles remain in the container, the one proximate to the partition plate will press upon the wire end 40, thereby holding the finger 37 away from an interfering position within the coin chute, so that during normal conditions of use coins may be introduced into the machine.

Close to its receiving end the chute pursues an oblique course being provided at 42 with a switch by which coins of different 80 sizes or denominations are directed properly into two branch chutes 43 and 44 intended, for instance, to receive nickles and pennies, respectively. The delivery ends of these chutes are best shown in Fig. 15, where it 85 will be noted that the penny chute is provided with a lateral extension 45 closed as at 46. The bottom end of the chute 43, as well as the bottom side of the chute extension 45, is closed as by means of a gate 47 90 which, in the form shown, is carried upon two arms 48 each pivoted to a rod 49 that is mounted upon bracket supports 50. The arms 48 are acted upon by suitable spring means (not shown) so as to normally maintain the gate in closed position to prevent the discharge of coins from either of the chutes. At its upper end each arm is outwardly extended as at 51 in the form of 95 a cam which lies in the path of travel of one of the carriage bars 24 by which means the arms are moved as the carriage is raised, and again as it is lowered, to open the gate 47 so as to effect a discharge of all coins 100 into a box 52 which is positioned beneath the 105 gate.

The coin setting mechanism.

As already suggested, the present machine is adapted for operation only after coins 110 have been inserted of the required number and denomination. A means is accordingly provided for setting the mechanism to operate (1) with one to four pennies, (2) with one nickel, and (3) with one nickel and one 115 to four pennies, thus adapting the machine, in the capacity herein shown, to operate with from one to nine cents. A greater range or capacity would require merely that the parts to be hereinafter described be duplicated 120 or reportioned, according to the purpose in view.

As best shown in Fig. 15, the extension chute 45 is provided with a plurality of holes 125 53, spaced apart a distance about equal to 130

the diameter of one coin, within any one of which may be set a finger 54 that is formed by bending the end of a swinging rod 55 that is pivoted upon the partition plate as at 56. Preferably this rod is rather tightly secured in place so as to be movable from one position to another only after first springing its finger end away from the chute for the required distance preliminary to any adjustment. In this manner the finger 54 will remain adjusted to act as a stop for coins passing through the penny chute. In order that adjustments of this swinging rod may be conveniently effected, an opening 56 may be arranged in the partition plate of sufficient size to enable the fingers to reach through to make such manipulations as are necessary. It will be noted that all adjusting movements of the rod 55 may be performed from that side of the partition plate wherein the papers or other commodities are stored, so that the partition plate need not be removed from the container for this purpose.

According to the construction described, the rod 55 may be so adjusted as to maintain the first penny in operative position to coöperate with certain release mechanism which will presently be explained, this position being always at the lower end of the chute 44 and not in the chute 45 extending laterally therefrom; or the rod 55 may be so adjusted as to maintain either the second, third, or fourth penny in this operative position. For instance, as shown in Fig. 15, the parts are adjusted so that it is the second penny, denominated as A, that is operatively positioned, this being accomplished by setting the finger 54 in the hole 53 this is removed from coin A by a distance equal to the diameter of one coin, whereby the first coin itself acts to hold the second coin in operative position. The extension chute 45 may be of open character, as shown, or entirely closed, if preferred, and the same is true of the other chutes 43 and 44, except that at their lower ends, where coins are held in operative position, both chutes should be open to coöperate with certain mechanism to be presently discussed.

The carriage release mechanism.

Referring now to Figs. 4 and 13, the carriage is shown to be provided on its rear side with a horizontal latch bar 60 that lies forwardly of the front faces of the chutes 43 and 44. In coöperative relation to this bar are two latch members 61 and 62, the former adjacent the nickel chute and the latter adjacent the penny chute, each latch being provided with a head which forms a hook 63 that is carried upon a neck 64 from which extends an obliquely inclined shoulder 65 that rises from a body portion 66, all as clearly appears in Fig. 5. The lower ends

of each of these latches may be turned in the manner shown in Fig. 3 to provide in effect double walls through which extends a pintle 67 that is carried upon suitable brackets 68 secured to the partition plate. As by means of coil springs 69, each latch is held toward the bar 60, so that its body portion is engaged therewith, as indicated in Fig. 5. It is obvious that the carriage will be permitted to rise but a very slight distance before the latch bar 60 will be engaged by the neck 64, and held beneath the head 63 of each latch so as to prevent further elevation of the carriage.

As a condition precedent to the dispensing operation, it is required that both of the latch members be maintained in a retracted or inoperative position, so that the latch bar 60 may pass clear of them when the carriage rises. In Figs. 5 to 10 inclusive, I have represented diagrammatically a means for rendering both latch members inoperative only when the proper coins have been introduced into the machine, and further a means for effecting adjustments in the number or valuation of the coins desired for operating the machine, as will now be explained.

I employ two arms 70, each of which is pivoted to a bracket support 71 which is adjustably secured, as by means of a stud and set screw, or otherwise, within a slot 72 having three notches 74 formed transversely thereof. Each bracket support may be adjusted from the rear side of the partition plate at any one of the three notches so as to thereby regulate the height of a lock bar 75 which extends between the lower ends of the two arms 70. Through alined openings 76 and 77, one in each of the two latch members 61 and 62 respectively, this lock bar extends, the various positions that it may assume within such openings being represented in Figs. 5 to 10. The opening 76 within the nickel latch (see Fig. 12) is offset in form to provide in effect upper and lower slots 78 and 79 respectively, between which is a widened area bounded by oblique edges 80 which tend to guide the lock bar 75 from one slot to the other. In each of the two slots, the bar 75 is adapted to remain motionless, but in the intermediate space it may shift laterally to aline with either slot. The opening 77 in the penny latch is similarly formed in its lower portion to provide a slot 81, but elsewhere is widened as at 82, a single oblique edge 83 being provided as shown. Within this opening the bar 75 may shift laterally, except when disposed within the slot 81, to aline with either slot 78 or 79 in the other latch. By means of the three notches 74, and parts associated therewith, the bar 75 may be vertically adjusted within any one of the three positions noted within the openings 76 and 77.

Each latch is further formed with an abutment 84 adapted for projection between the flanges of the chutes 43 and 44 so as to lie immediately adjacent the coins therein that occupy operative positions relative to the mechanism under description. When the carriage first starts to move upwardly, and as soon as the latch bar 60 begins to ride upon the latch shoulders 65, these abutments 10 are adapted to engage with the operative coins to hold the latch members back from interfering position with the carriage so as to permit of its complete elevation.

Operation.

15 While the operation of the present machine has already been explained in part, I will now outline the successive movements of the several mechanisms under all the conditions normally encountered.

20 To operate with one nickel and one or more pennies: The rod 55 is set to position the finger 54 within a desired opening 53 so as to determine the minimum number of 25 pennies requisite for operation. If, for instance, adjustment is desired for a nickel and two pennies, the bar 55 will occupy the position shown in Fig. 15. The two brackets 71 are also adjusted at the middle notch 74 so as to dispose the lock bar 75 in an intermediate position between the ends of the two openings 76 and 77, as shown in Fig. 5. When the proper coins have been deposited, both abutments 84 will stand adjacent the 30 operative coins, so that when the carriage starts to rise, the two latch members will be withheld from swinging inwardly to locking position. With continued movement of the carriage, the cams 51 will be engaged to open 35 the gateway 47 for the discharge of all coins from the chutes into the coin box 52. Again on the downward stroke of the carriage these cams will be engaged to repeat the clearing operation, this double action assuring a sufficient interval of time for the release of all 40 coins that have been introduced into the machine.

With the parts adjusted as described, it 45 will be impossible to operate the machine with any other combination of coins—except, of course, when more of these particular coins are used than is needful. This may best be understood by reference to Fig. 6 wherein is exhibited the relation of the parts 50 which obtains when an attempt is made to operate with one or more pennies, but without the necessary nickel. In this instance, it will be noted that because of the absence of the necessary operative coin, the abutment 84 on the nickel latch is ineffective to 55 withhold the latch 61 from locking with the carriage when it first commences to rise. Consequently before the latch bar 60 is elevated through any appreciable distance, the 60 nickel latch 61 is swung into locking posi-

tion, as indicated in Fig. 6. In executing this movement the lock bar 75 is shifted laterally within the opening 77 (wherein it has freedom of movement in the intermediate position) as it is carried inwardly with 70 the movement of the latch member 61. If the relation between the lock bar and opening 77 were not such as to permit of this shift in position, the nickel latch would, through the agency of the bar 75, be also withheld 75 from locking with the carriage. In the circumstances noted, it is impossible to operate the machine due to the use of an improper combination of coins.

To operate with one or more pennies: The 80 rod 55 is set to position the finger 54 within a desired opening 53 so as to determine the minimum number of pennies requisite for operation. The two brackets 71 are also adjusted at the lowermost notch 74 so as to dispose the lock bar 75 within the slots 79 and 81, as shown in Fig. 7. When the proper number of pennies have been deposited, the abutment 84 on the latch member 62 will stand adjacent the operative coin so that 85 when the carriage starts to rise this latch will be withheld from swinging inwardly to locking position; and inasmuch as the lock bar 75 in the lowermost adjustment cannot shift laterally within either of the two slots 90 79 and 81, it acts to withhold the other latch member also from swinging into locking position. Both latches being so withheld through the medium of a single operative 95 penny, the carriage is free to travel through 100 its complete cycle. The remaining movements are in all respects the same as those previously explained.

With the parts adjusted as described, it 105 will be impossible to operate the machine with any other combination of coins—except, of course, when one or more nickels and an excess number of pennies are used additionally. This may best be understood by reference to Fig. 8, wherein is exhibited the 110 relation of the parts which obtains when an attempt is made to operate with less than the required number of pennies. In this instance, it will be noted that because of the 115 absence of the necessary operative coin, the abutment 84 on the penny latch is ineffective to withhold the latch 62 from locking with the carriage when it first commences to rise. The nickel latch in these circumstances will also tend to lock with the carriage as well.

To operate with one nickel: The rod 55 120 may be positioned wherever desired, as it is not presumed that pennies will be deposited for this operation. The two brackets 71 are adjusted as the topmost notch 74 so as 125 to dispose the lock bar 75 within the narrow upper slot 78 of the nickel latch and within the widened upper end 82 of the opening in the penny latch, as best shown in Fig. 9. Under these conditions, the bar 75 will be 130

held forwardly within the end 82 of the penny latch opening, this position being determined by the location of the upper slot 78 within the nickel latch wherein the bar 5 is confined. When a nickel has been deposited, the abutment 84 on the latch member 61 will stand adjacent this coin, so that when the carriage starts to rise, this latch will be withheld from swinging inwardly to locking 10 position; and inasmuch as the lock bar 75 in this uppermost adjustment is already held forwardly within the opening 77 in the penny latch, it acts to withhold this latch also from swinging into locking position. 15 Both latch members being so withheld through the medium of a single operative nickel, the carriage is free to travel through its complete cycle. The remaining movements are in all respects the same as those 20 previously explained.

With the parts adjusted as described, it will be impossible to operate the machine with any other combination of coins—except, of course, when one or more pennies 25 or an excess number of nickels are used additionally. This may best be understood by reference to Fig. 10, wherein is exhibited the relation of the parts which obtains when an attempt is made to operate with one or 30 more pennies, but without the necessary nickel. In this instance, it will be noted that, because of the absence of the necessary operative coin, the abutment 84 on the nickel latch is ineffective to withhold the latch 35 61 from locking with the carriage when it first commences to rise; and, although the penny latch may be withheld from locking with the carriage, yet it cannot restrain the action of the nickel latch because of the 40 widened upper end 82 of its slot 77 which permits the lock bar 75 to freely shift laterally as required by the movements of the latch member 61.

45 General observations.

The present machine embodies a simple assembly of parts all of which are conveniently mounted on one side of the partition plate and away from the compartment within 50 the container where the articles to be dispensed are stored. In other words, it is not necessary to have access to the compartment wherein the mechanism itself is located in order to make adjustments affecting the 55 combination of coins requisite for operation.

It is a feature of advantage in this invention that use is made of two latches, each arranged independently of the other, but either adapted to be controlled by the other 60 under proper conditions. Either of these latches may engage the carriage to lock the same against movement except when the proper combination of coins has first been deposited. The various parts of the operating mechanism are, furthermore, conven-

iently mounted upon the partition plate in a separate compartment that is not exposed when the cover is raised for the replenishment of articles to be dispensed. As a unit, the entire operating mechanism may be readily withdrawn from the container in case it is desired to effect any repairs or adjustments. 70

While I have described and illustrated a machine that is adapted for operation with 75 coins of different denominations, such as pennies and nickels, it is obvious that changes in the number or proportion of its parts would render the device suitable for operation with coins of other denominations. 80 Inasmuch as such details do not require any substantial modifications in the operating principle, I have deemed it unnecessary to show other constructions, but consider that the present disclosure should suffice as an 85 exemplification of the invention in its preferred form.

I claim:

1. In a machine of the kind described, the combination of a movable carriage, a plurality of independent latch members, each adapted to check movement of the carriage, means connecting the several latch members, and adjustable relative to them all, adapted in different positions of adjustment to restrain operation of all the latch members, and coin mechanism adapted to coöperate with any one or more of said latch members to thereby restrain operation of all of them with initial movement of the carriage, substantially as described. 90 95

2. In a machine of the kind described, the combination of a movable carriage, a plurality of latch members, each adapted to check movement of the carriage, and each 100 formed with an opening registering with the other, a bar extended through the openings in each latch member and being adjustable therewithin, the configuration of said openings being such as to lock together all 105 the latch members when the bar is in a selected adjusted position, and to unlock certain of them when the bar is in other selected adjusted positions, and coin mechanism coöperating with a selected latch member for operating through the medium of the bar with initial movement of the carriage, to lock all the latch members against movement, substantially as described. 110 115

3. In a machine of the kind described, the 120 combination of a movable carriage, latch mechanism for checking movement of the carriage, and means for holding said latch mechanism inoperative to permit complete movement of the carriage, including coin 125 mechanism having a plurality of chutes each for the reception of coins of a particular denomination, means within each chute for holding a selected coin in position to coöperate with the latch mechanism to main- 130

tain the same inoperative, and means operable by movement of the carriage for effecting a discharge of all coins from the chutes, substantially as described.

5 4. In a machine of the kind described, the combination of a container within which is vertically mounted a removable plate having its upper end turned to lie adjacent one of the container walls, the container being 10 formed with a slot above the turned end of the plate which communicates with a compartment that lies rearwardly of the plate, means secured to the plate and lying wholly on the side thereof which is beneath its 15 turned end for dispensing articles that are housed within the container compartment that lies on the opposite side of the plate, said means being coin controlled and being adjustable from the side of the plate facing 20 the article compartment to operate only with a selected combination of coins, substantially as described.

5. In a machine of the kind described, the 25 combination of dispensing mechanism, a plurality of independent locking means for restraining operation of the dispensing mechanism, coin mechanism including means wherein the body of a coin acts to interfere with movement of other parts whereby 30 all of the locking means are restrained to permit operation of the dispensing mechanism, and adjusting means for setting the coin mechanism to operate only with a desired combination of coins, substantially as 35 described.

6. In a machine of the kind described, the 40 combination of a movable carriage, a latch movably mounted on the machine and adapted to engage the carriage to prevent movement thereof, a chute arranged to conduct a coin to a definite position in proximity to the latch at which point the chute is open to expose the coin, means for holding the coin stationary during movement of the carriage through a predetermined distance, and means associated with the latch adapted to engage the coin for restraining operation of the latch to thereby permit movement of the carriage, substantially as described.

50 7. In a machine of the kind described, the combination of a movable carriage, a latch adapted to engage the carriage to prevent movement thereof, a chute arranged to deliver coins into proximity with the latch 55 at which point the chute is open to expose a single coin, means associated with the chute for predetermining which coin shall be exposed within the chute, and means associated with the latch adapted to engage the exposed coin for restraining operation of the latch to thereby permit movement of the carriage, substantially as described.

8. In a machine of the kind described, the 60 combination of a plate on which is mounted a chute having its delivery end formed to lie

in a plane which approximates the horizontal, a rod pivoted to the plate and having a finger at one end adapted to engage with any one of a plurality of openings formed in the delivery end of the chute so as to constitute 70 a stop for coins passing therethrough, the chute being open at one point to expose a coin that is definitely held by the finger, a latch having an abutment adapted to contact with the coin whereby movement of the latch is restrained, and dispensing mechanism in operative relation to the latch adapted to be restrained thereby except when its abutment lies against a coin, substantially as described.

9. In a machine of the kind described, a 80 plate on which is mounted a chute having its delivery end disposed within a plane that approximates the horizontal, a gate at the lower edge of the delivery end of the chute through which coins may discharge, a rod 85 pivoted to the plate, and carrying at its free end a finger adapted to lie within any one of several openings that are formed in the delivery end of the chute so as to constitute a stop for coins passing therethrough, the 90 chute being open at one point to expose a coin that is definitely positioned by the finger at that place, a latch member pivoted to means that are carried by the plate and having an abutment in operative relation to said exposed coin, dispensing mechanism whose operation is subject to control of the latch, the latter being held inoperative except when a coin engages the abutment thereof, and means operated by movement of the dispensing mechanism for opening the gate for discharging coins from the chute, substantially as described.

10. In a machine of the kind described, the combination of a movable carriage, latch 105 mechanism for checking movement of the carriage, and means for holding the latch mechanism inoperative to permit complete movement of the carriage including coin mechanism having a plurality of chutes each 110 for the reception of coins of a particular denomination, and means within each chute for holding a selected coin in position to cooperate with the latch mechanism to maintain the same inoperative, substantially as 115 described.

11. In a machine of the kind described, the combination of dispensing mechanism, a plurality of independent locking means for restraining operation of the dispensing mechanism, means for withholding all the locking means from locking position when the dispensing mechanism is in a normal position of rest, coin mechanism including means wherein the body of a coin acts to interfere 125 with movement of other parts when operation of the dispensing mechanism is started, whereby all of the locking means are withheld from locking position to permit complete operation of the dispensing mechanism, 130

- and adjusting means for setting the coin mechanism to operate only with a desired combination of coins, substantially as described.
5. 12. In a machine of the kind described, the combination of a movable carriage, a latch movably mounted on the machine and adapted to engage the carriage to prevent movement thereof, means for withholding the latch from locking position when the carriage is in its normal position of rest, a chute arranged to conduct a coin to a definite position in proximity to the latch at which point the chute is open to expose the coin,
- 10 means for holding the coin stationary during movement of the carriage through a predetermined distance, and means associated with the latch adapted to engage the coin when operation of the carriage is started for withholding the latch from locking position
- 15 to thereby permit complete movement of the carriage, substantially as described.
13. In a machine of the kind described, the combination of a movable carriage, a latch adapted to restrain any but a limited movement of the carriage, means for withholding the latch from locking position when the carriage is in its normal position of rest, means for retaining a coin adjacent the latch in stationary relation thereto, and means associated with the latch adapted to engage the coin when operation of the carriage is started for withholding the latch from locking position to thereby permit complete movement of the carriage, the coin and means engaging therewith remaining in stationary relation to each other during movement of the carriage through a predetermined distance, substantially as described.

EDWARD SCHULTZ.
